UNITED STATES PATENT OFFICE.

HARRY G. DAVIS, OF PHILADELPHIA, PENNSYLVANIA, ASSIGNOR TO GEORGE L. CAMPBELL, OF PHILADELPHIA, PENNSYLVANIA.

TIME-CONTROLLED ACTUATING DEVICE.

Application filed March 22, 1920. Serial No. 367,585.

To all whom it may concern:

Be it known that I, HARRY G. DAVIS, a citizen of the United States, residing at Philadelphia, in the county of Philadelphia and State of Pennsylvania, have invented 5 certain new and useful Improvements in Time-Controlled Actuating Devices, of which the following is a specification.

My invention relates to automatic cut off 10 for valves, and particularly to a time controlled mechanism, by which the valves is automatically actuated at the termination of a predetermined period of time.

The object of the invention is to simplify 15 the structure as well as the means and mode of operation of such devices, whereby they will not only be cheapened in construction, but will be more efficient in use, automatic in operation, positive in action, easily and 20 readily set and controlled, and unlikely to get out of repair.

A further object of the invention is to provide a mechanism of this character in 25 which the setting operation will afford the necessary actuating power.

A further object of the invention is to provide a gravity operating mechanism which will obviate the necessity for springs or winding mechanism, and to further provide improved driving means whereby the 30 mechanism will be relieved from abnormal or excessive strains.

With the above primary and other incidental objects in view as will more fully appear in the specification, the invention consists of the features of construction, the parts and combinations thereof, and the mode of operation or their equivalents as herein-after described and set forth in the claims.

Referring to the drawings, Fig. 1 is a top 40 plan view of the assembled apparatus. Fig. 2 is a side elevation thereof, with the actuating arm in its set position, and indicating by dotted lines the position of the arm at the moment of its release. Fig. 3 is an end elevation of the construction shown in Figs. 1 and 2. Fig. 4 is an enlarged detail view somewhat diagrammatic in character illustrating the gear train. Fig. 5 is a detail 45 sectional view of the frictional driving connection by which undue or excessive strains are automatically compensated. Fig. 6 illustrates a modification.

Like parts are indicated by similar characters of reference throughout the several 55 views.

While the automatic valve operating device forming the subject matter hereof was 60 designed especially for cutting off the fuel supply at the end of a predetermined operating period, to the garbage and refuse incinerator disclosed in co-pending application Serial No. 344794, it is capable of general 65 application. It may be employed not only as a cut off, but also by a mere reversal of 70 the valve operating lever or of the movable valve element, for the purpose of turning such valve on. In addition to its use in connection with the incinerator referred to, it may be utilized to cut off the fuel supply to 75 a gas range, at the end of a predetermined cooking period, or may be used to reduce the fuel supply to a furnace, after a preliminary pre-heating period. Likewise it may be utilized to turn on a fuel supply where a 80 pilot burner is employed, for the purpose of starting a cooking operation at a predetermined time or for turning up the fuel supply to a furnace at an early morning hour without attention. The device will likewise 85 find a wide range of use in the mechanical or industrial arts for the regulation of annealing ovens or in the heat treatment of metals. The device may be applied not only to gas lines, but also to steam pipes for turning 90 steam on or off after a predetermined interval of time. It may be also utilized in water distribution systems for instance, in association with an automatic sprinkler for lawns or gardens. By this means the 95 sprinkler may be set to operate for a given interval of time and left without further attention. The apparatus is not only capable of use as a valve operating means, but may be utilized as a time controlled operator 100 for an electric switch. It may be utilized for the automatic regulation of furnace dampers which ordinarily are left open for an interval of time after supplying fresh fuel. The present device may be made to set 105 the dampers after any predetermined preliminary combustion period. The apparatus may be likewise utilized for shifting belts, or operating a clutch into or out of driving engagement or for other analogous purposes. In view of the wide range of useful

ness, the device is to be understood as not limited to use as an automatic cut off for valves, and the application of the device to a valve as shown in the drawings is to be 5 considered only as illustrative of the operation, and in no sense as limiting the apparatus to such use.

The apparatus is gravity operated under the influence of a descending weight. The 10 apparatus is set and energy supplied by lifting the weight to different heights in accordance with the desired time interval, which shall elapse before the operation of the valve or other mechanism. By the construction disclosed, the use of springs is 15 eliminated, as is also the necessity for winding or charging, and the possibility of failure to operate by the exhaustion of power in a mid-stroke position, is obviated.

20 In the application of the invention disclosed in the drawings 1 is a supply pipe for gas water or steam, having therein a control or cut off valve 2. The apparatus forming the subject matter hereof may be mounted or supported in any suitable way in proximity to the valve 2. For convenience, it has been shown carried upon a supporting bracket comprising a halved sleeve 3, clamped upon the pipe line 1. As shown in 25 the drawing the supporting bracket 3 encloses the T coupling 4 of an auxiliary fuel supply line 5, which supplies a pilot burner. It will be understood that this is not an essential feature of the invention, but is shown 30 merely for illustrative purposes. The halved sleeve is clamped in place by the clamp bolts 6. However, to insure against rotation, the end of the sleeve is preferably 35 formed with a polygonal recess in which is engaged one of the hexagonal heads of the control or cut off valve 2. The upper half of the bracket sleeve 3 carries an upstanding flange 7 with which is engaged the main frame plate 8. The lower half of the bracket 40 3 is provided with a projecting stop arm 9, which arrests the weighted actuating arm at the limit of its movement.

The operative parts of the mechanism are 45 carried upon the opposite side of the vertical main frame plate 8. Secured to the outer face of the frame plate 8 is a housing or gear cover 10, in which is formed a bearing for one end of the pivot or trunnion stud 11 upon which is pivoted for free oscillatory 55 movement the weighted actuating arm or pendulum 12. This weighted actuating arm 12 is mounted within the housing or cover 10 as is also an actuated ratchet wheel 13. 60 The ratchet wheel 13 is also mounted upon the pivot or trunnion stud 11 and is interconnected with the primary gear 14 of the speed governing mechanism upon the opposite side of the frame plate 8. Interposed 65 between the ratchet wheel 13 and the pri-

mary gear 14, is a spacer collar 15 extending thru a suitable opening in the frame plate 8, and fixedly connected with the ratchet wheel 13 and primary gear 14 by means of transverse screws 16. The construction is such that the ratchet wheel 13 and primary gear 14 rotate in unison under the influence of the weighted actuating arm 12 as hereafter described upon the bearing afforded by the intermediate collar 15 within the frame plate 8. The pivotal trunnion stud 11 projects thru a central bore 17 in the interengaged ratchet and gear wheels 13 and 14, and may be fixedly engaged for rotation in unison therewith, or may be 70 loosely journaled therein whereby the said wheels rotate independent of the trunnion stud which is supported at one end in the gear housing 10, the other end being engaged 75 in the frame plate 21. This connection is not material and either of the alternative constructions may be employed. The actuating arm 12 carries a pivoted weighted pawl 18, pivoted to said arm at 19, and adapted to engage the teeth of the ratchet wheel 13. The pawl 18 is held in engagement with the ratchet wheel 13 during the operating interval by the weighted portion 20 of such pawl, which tends to swing the pawl about its pivot 19 toward the ratchet wheel 13. There 80 is thus provided a driving engagement between the weighted arm 12 and the ratchet wheel 13 which tends to rotate the wheel 13 and with it the primary gear 14 of the governing frame as the weighted arm 12 descends under the influence of gravity. To govern the movement of the actuating arm and retard it to a predetermined timed ratio, a gear train leads from the primary gear 14 to a flutter escapement. To support such gear element there are provided auxiliary frame plates 21 and 22, carried upon studs 23, and separated one from the other and from the main frame plate 8 by interposed 85 spacers 24. The relation of these auxiliary plates is such that the primary gear 14 is positioned intermediate the innermost auxiliary frame plate 21 and the main frame 90 plate 8, where it meshes with a gear pinion 25 fixedly mounted upon a shaft 26 journaled in the main frame plate 8 and the outer auxiliary frame plate 22. There is also carried by this shaft 26 a frictionally driven gear 27, interposed between a friction driving head 28 secured upon the shaft 26 by means of a transverse pin 29 or other suitable means and an adjustable friction plate 30 keyed upon the shaft 26 and adjustable toward the head 28 under the influence of an adjusting nut 31 screw threaded upon the shaft 26. The gear element 27 may thus be clamped between the elements 28 and 30 with more or less pressure whereby it may yield under excessive driving 95 100 105 110 115 120 125 130

strains or undue resistance, to prevent breakage. The governing gear train may be of any extent or involve any desired speed reduction or gear ratio. As illustrated in the drawings the frictionally driven gear element 27 intermeshes with a gear pinion 32 interconnected with a larger gear 33. The gear 33 in turn intermeshes with a gear pinion 34 rotating in unison with a major gear element 35. The latter gear in turn intermeshes with a succeeding pinion 36 which carries a major gear element 37. The last mentioned gear 37 intermeshes with a pinion 38 to which is connected the escapement ratchet 39 engaged by the pallets 40 of an anchor escapement comprising the oscillator 41 and flutter plate or vane 42. This governing train and escapement mechanism has been here shown and described for illustrative purposes only, and it is to be understood that any other form of speed governing device may be utilized. For instance, a frictional or brake mechanism, a centrifugal governor or a counter balancing weight might be substituted without changing the operation nor the result accomplished.

For guidance in setting the mechanism for various time intervals before final operation one edge of the main frame plate 8 has been shown as of arcuate form concentric with the center of operation of the actuating arm 12, and is provided with a series of graduations 43 indicating units of time. A pointer 44 carried by the actuating arm 12 coacts with the graduations 43. By lifting the weighted arm 12 manually until the pointer 44 agrees with the graduation corresponding to the desired time interval and releasing the arm the mechanism will operate thru the indicated period before tripping the valve or other operated device. As shown in the drawings the time value of the graduations increase upwardly whereby the higher the arm 12 is elevated in setting the mechanism the longer will be the time interval before it reaches the tripping point. In the event that thru accident or mistake the arm 12 is elevated above the desired indication or if it is found that the time interval has been over estimated, the actuating arm may be readjusted by manually tripping the pawl 18 by elevating the weighted end thereof and allowing it to reengage the ratchet wheel 13 at a lower point. However, should the operator merely press down the elevated actuating arm, no harm will be done since the frictionally driven gear element 27 will yield to protect the escapement.

The apparatus having been set by the manual elevation of the actuating arm 12, this weighted arm will upon release gradually descend at a slow rate of speed under control of the governing gear train and escapement. As the actuating arm reaches the zero point of the scale in its descent, an anti-

friction roller 45 or in the absence of the roller a mere trip stud, carried by the weighted portion of the actuating pawl 18 engages an arcuate cam bar 46 secured to the frame plate 8 concentric with and beneath the ratchet wheel 13. The engagement of the roller or stud 45 with the cam bar 46 oscillates the pawl 18 out of engagement with the ratchet wheel 13 thereby releasing the weighted actuating arm 12 from the control of the gear train and escapement. This release of the actuating arm occurs when the arm is in a position somewhat above a forty-five degree angle. The control valve 2, electric switch or other operated device is provided with an oscillatory lever 47 which projects into the path of travel of the actuating arm 12. As the weighted arm 12 is disengaged from the control mechanism and falls under the influence of gravity it engages the operating arm or lever 47 and carries this arm downward with it, thus transmitting to the arm and parts connected therewith a partial rotation. As shown in the drawing the operated arm or lever 47 is actuated by the weighted arm 12 thru a quarter rotation from a substantially horizontal position to a substantially vertical position. It is obvious that this arm or lever may be actuated thru a somewhat greater or a less degree of movement. At the limit of movement the weighted arm 12 is arrested by the stop arm 9 carried by the supporting brackets 3, where it remains until manually set for the next operation.

It is obvious that the contacting elements of an electric switch or circuit breaker may be connected with the pivoted arm 47 or this arm may be utilized as the primary element of a belt shifting mechanism, a damper operating means, a clutch control device or other analogous mechanism.

While the pawl and ratchet connection of the actuating arm 12 with the governing train is the preferred embodiment of the invention, it is obvious that other connections may be employed which will afford an automatic release of the arm 12 at the predetermined point in its path of travel. As an illustration of such modification, there is shown in Fig. 6 a detail view of a mutilated gear device which will afford the desired result. In this construction a gear pinion 50 is substituted for the ratchet wheel 13. In lieu of pivoting the operating arm 12 upon the trunnion stud 11, the arm is pivoted in offset or eccentric relation thereof and is rigidly connected with a gear sector 51. The teeth of which mesh with the pinion 50. The series of teeth of the sector 51 are limited to such extent that in the intermeshing action of the sector, and pinion, the pinion passes beyond the limit of the series of teeth when the arm 12 has reached the releasing point, allowing the arm to fall idly under the influ-

ence of gravity. In setting this device the arm is pulled upward as in the previous construction which causes the teeth of the sector to intermesh with those of the pinion 5 and drives the pinion temporarily in reverse direction during the receding operation. This reversal of the pinion 50 is transmitted thru the entire governing train, or is compensated for by the slippage of the reactionary driven element 27. The arm 12 having been raised to the desired height is released and thereafter operates by influence of gravity thru the gear sector 51 to drive the pinion 50 and the governing train until the end of the series of sector teeth is reached. While a sector has been shown, it is obvious that a mutilated gear or one having several teeth removed may be utilized. Likewise in the event that the gear pinion 20 is of sufficient size that it will make less than one revolution during a full operation, this pinion 50 may be mutilated by removal of teeth to effect the release of the arm. The latter construction is merely a reversal of that shown in Fig. 3 and hence will be obvious without illustration.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific details shown, but that the means and construction herein disclosed comprise but one of several modes of putting the invention into effect, and the invention is therefore claimed in any of its forms or modifications within the legitimate and valid scope of the appended claims.

Having thus described my invention, I claim:

1. In a time controlled actuating mechanism of the character described, a gravity operated prime mover, a member to be operated extending into the path of travel of said prime mover, a governor mechanism for retarding the movement of the prime mover through a portion of its travel under the influence of gravity, means for interengaging the prime mover and governor mechanism in different relations for different predetermined degrees of controlled movement, and means for automatically disconnecting the prime mover from the governing means before it has reached the limit of its range of movement whereby the remainder of its

movement is effected at an accelerated speed, said member to be operated being engaged by the prime mover through an additional degree of movement.

2. In a time controlled actuating mechanism of the character described, a gravity operated prime mover, governing means for retarding the progress of the prime mover during the initial period of its travel, variable clutch means for engaging the prime mover and governing means in different relations, means for disconnecting the governing means at a predetermined point in the path of travel, said prime mover having a variable range of movement prior to such disengagement, means for predetermined the variable degree of retarded movement, and a member to be operated extending into the path of travel of the gravity operated prime mover and engaged thereby during its unrestrained final movement after being disengaged from the governing means.

3. In a time controlled actuating mechanism, a gravity operated prime mover, a governing mechanism for retarding the progress of the prime mover during an initial portion of its travel, means for automatically disengaging the prime mover with the governing means at a predetermined point in its path of travel, an adjustable detent by which said prime mover is engageable with the governing means different measured distances in advance of said point of disengagement and a member to be operated extending into the path of travel of the prime mover and actuated thereby during the unrestrained final movement thereof subsequent to its disengagement from the governing means.

4. In a time controlled actuating mechanism, a gravity operated lever, a regulated wheel rotating always in the same direction with which the lever is concentrically pivoted, means for detachably engaging the lever with the wheel in different radial positions for movement in unison, means for disengaging said members at a predetermined point in their path of travel, and a member to be operated extending into the path of unrestrained travel of the lever and actuated by the impact thereof after being disengaged from the regulated member.

5. In a time controlled actuating mechanism, a gravity operated prime mover, a movable regulated member, a pawl and ratchet connection between said members whereby they may be interengaged for movement in unison in different positions of relative adjustment, a stationary trip member adapted to disengage the pawl at a predetermined point in the path of travel of said members whereby the prime mover is permitted further unrestrained movement independent of the regulated member, and a member to be actuated extending into the

path of travel of the prime mover and actuated thereby during its movement subsequent to its release from the regulated member.

5 6. In a time controlled actuating mechanism, a gravity operated prime mover, a governing means, means actuated thereby for detachably engaging the prime mover with the governing means at different elevations, 10 means for disengaging said prime mover at a predetermined point in its path of travel, the elevation of the point of engagement above the point of disengagement being variable to determine the time interval of 15 operation, and a member to be actuated which is engaged by the prime mover subsequent to its disengagement.

7. In a time controlled actuating mechanism, a weighted swinging arm, a ratchet 20 wheel, governing means controlling the rotation of the wheel, a pawl carried by the arm and engageable with the ratchet wheel in various radial positions, means for disengaging said pawl at a predetermined mid-stroke 25 position, and a member to be actuated engaged by the arm when released from the wheel.

8. In a time controlled valve operating 30 mechanism, the combination with a valve of an operating member therefor, a swinging arm into the path of travel of which the valve operating member extends, said parts being independent of each other, means for 35 retarding the swinging movement of said arm for predetermined periods of time, including a governor mechanism for movement in unison, a cam in the path of travel of the detent by engagement with which the detent is disengaged from the governing 40 means to release the arm for swinging engagement with the valve operating member.

9. In a time controlled valve operating 45 mechanism, the combination with a member to be operated and an operating member therefor, of a weighted member into the path of which the operating member extends, time controlled governing means actuated by the weighted member and temporarily controlling the movement thereof, said weighted member being released after varying predetermined intervals of time to release said weighted member for engagement with the valve operating member.

55 10. In a time controlled actuating mechanism of the character described, the combination with a member to be actuated, and a movable operating member therefor, of a time governor, a gravity operated actuator into the path of travel of which the operating member extends, said gravity operated actuator also furnishing the motive power for said governor, a releasable detent for engaging said actuator in different positions

of adjustment in relation with the time governor, to predetermine the interval of time prior to its release, and means to automatically release the actuator after a predetermined period of time according to the position of relative adjustment thereof in relation with the time governor.

65 11. In a device of the character described, the combination with a member to be actuated and a movable operating member therefor, of a swinging weighted arm, a concentric time controlled member with which the arm is detachably engageable in different radial positions, a detent for so engaging said arm and time controlled member, a stop engaged by said detent upon the unison movement of said arm and time controlled member to a predetermined position, by which the detent is withdrawn to release the arm, said arm upon release being adapted to impinge upon and operate said movable 80 operating member.

75 12. In a device of the character described, the combination with a member to be actuated, of a gravity operated actuator therefor, a time controlled member, a detent for 90 interengaging the actuator and time controlled member in different relative positions of adjustment to predetermine different periods of time prior to the moment of release, and a stop member 95 for releasing the detent when the actuator and time controlled member have moved in unison to a predetermined point, whereupon the gravity operated actuator in its free movement will impinge upon and operate 100 said member to be actuated.

105 13. In a device of the character described, the combination with a member to be actuated, of a gravity operated actuator therefor, a time controlled member with which said actuator is detachably engageable, governor means connected therewith, and a frictional driving connection between the governor and time controlled member by which the actuator and time controlled member 110 may be adjusted independent of the governor.

115 14. In a device of the character described, the combination with a member to be actuated, of a gravity operated actuator therefor, a time controlled member with which said actuator is detachably engageable, governor means connected therewith, and a yielding connection intermediate the governor and actuator permitting independent movement of the latter under abnormal stress.

In testimony whereof I have hereunto set my hand this 3rd day of March, A. D. 1920.

HARRY G. DAVIS.
